UNITED STATES PATENT OFFICE

ISIDORE PETER SMITH, OF TOLEDO, OHIO, ASSIGNOR TO THE HETTRICK MANUFACTURING COMPANY, OF TOLEDO, OHIO, A CORPORATION OF OHIO

WALL TENT

Application filed September 6, 1930. Serial No. 480,091.

This invention relates to tents and an object is to produce a tent in which certain walls may be unfastened and thrown back and additional walls of foraminous material are associated with the separable walls in order to keep out insects, etc., from the inside and permit free circulation of air and a substantially unimpaired outlook when the separable walls are thrown back.

Another object is to provide a cover wall for the top wall of a tent which may be of stronger material than the top wall and, when spread over the top wall, may be fastened in such manner that the strain of the guy ropes of the tent is transmitted to the cover wall instead of to the weaker top wall.

Further objects will hereinafter appear and by way of illustration, an embodiment of the invention is shown on the accompanying drawings, in which—

Figure 1 is a fragmentary perspective view of a tent embodying my invention;

Figure 2 is a fragmentary side elevation of the tent showing the cover walls rolled up; and

Fig. 3 is an enlarged detail view showing the detachable connection between the hook on the guy ropes and the cover wall.

The illustrated embodiment of the invention comprises a wall tent consisting of side walls 1, top walls 2 and front wall 3 of net material, such as bobbine, reinforced by canvas strips 4. The edges are also reinforced by canvas strips 5 and the jointure between the top and side walls is reinforced by canvas strips 6, to which are connected the usual guy ropes 7 extending through eyes 8 in the jointure strips 6. A longitudinally disposed canvas strip (not shown) extends across the ridge of the tent and is provided with eyes to receive the usual supporting poles 9. As shown, the front wall 3 of the tent is covered by a canvas outer wall 10, which is suitably sewed to the adjacent reinforcing canvas strips 5.

Extending over the top walls 2 of the tent is a cover wall 11 which may be of relatively heavy waterproof canvas. The cover wall 11 is connected to the ridge strip of top walls 2 by lines of stitching 12, the remaining sides

being separable from the top walls 2 so that either or both portions of the cover wall 11 may be rolled up or thrown back. For example, one or both portions of the cover wall 11 may be propped out by poles 12.

Since the top walls 2 are of relatively weak material, it is desirable that the strain of the guy ropes 7 be transmitted to the cover wall 11 when the latter is in place, in order to strengthen the structure. For this reason, hooks 13 are slipped over the guy ropes 7 and are adapted to receive rings 14 connected by tabs 15 to the under side of the cover wall 11. By slipping the rings 14 over the hooks 13 the strain of the guy ropes 7 is imparted to the cover wall 11. The hooks 13 may be suitably connected to the guy ropes 7, but are preferably fixed in the desired position, so that the strain of the guy ropes may be transmitted through the hooks to the wall 11. In order to more securely fasten the cover wall 11 to the tent structure, cooperating snap fasteners 16 on jointure strips 6 and the under side of wall 11 are provided. Similar fasteners 17 are provided on the side edges of the cover wall 11.

Cover walls 18 may also be provided for the side walls 1 of a tent and, as shown in Fig. 2, these may be rolled up and held by suitable ties 19 depending from the jointure strip 6. It is apparent that with this tent cover walls 11 and 18 may be rolled up or thrown back, but the remaining walls of foraminous material are effective for keeping out insects and other disturbing elements, and afford free circulation of air throughout the tent, as well as give a substantially unimpaired outlook from the inside of the tent. This is considered an important advantage over the ordinary canvas wall tent, which is well-known to become extremely uncomfortable on the inside from the lack of proper circulation and sunlight. This invention overcomes the objections to the tents generally in use and constitutes a valuable advance in the art. The cover walls provide adequate protection against the elements and also enhance the strength of the tent when fastened in place, since the strain of the guy ropes is in the main transmitted to the outer

or cover wall, thereby relieving the strain from the foraminous top walls. It should be observed, however, that the guy ropes 7 are so connected that the strain is not transmitted directly to the foraminous material, but through the reinforcing or strengthening strips 4, 5 and 6.

It is to be understood that numerous changes in details of construction, arrangement of choice of materials may be effected without departing from the spirit of the invention, especially as defined in the appended claims.

What I claim is:

15. 1. A tent having top and side walls, guy ropes extending from the jointure of said walls, a cover wall for said top wall but separate therefrom on three sides, a connection between the upper edge of said cover and said top walls, and detachable fastening means on said guy ropes for connecting said cover wall thereto, thereby to transfer a portion of the strain from said top wall to said cover wall, when the latter is connected to said guy ropes.
20. 2. A wall tent having top and side walls, said top walls being of fabric foraminous material, a reinforcing fabric strip extending longitudinally of the ridge of said top wall, a fabric cover wall for said top wall, a connection between said cover wall and said fabric strip, fabric strips providing a jointure between said top and side walls, and detachable fastening means for connecting said cover wall to said jointure strips.
25. 3. A wall tent having top and side walls, a separable cover wall for said top walls, guy ropes leading from the jointure of said top and side walls, and fastening means on said guy ropes for detachably securing the cover wall thereto and relieving the strain from said top walls.
30. 4. A wall tent having top and side walls, jointure strips connecting said walls, a cover wall for said top walls of stronger material than said top walls, guy ropes leading from said jointure strips, hooks on said guy ropes, and rings on said cover wall for engagement with said hooks to relieve the strain from said guy ropes from said top walls.
35. 5. In a tent having top and side walls, jointure strips connecting said walls, a cover wall over said top wall, guy ropes leading from said jointure strips, and detachable fastening means on said guy ropes and cover wall respectively for transferring a portion of the strain of said guy ropes from said top wall to said cover wall.
40. 6. A wall tent having top and side walls, said top wall being of fabric foraminous material, a cover wall for said top wall, reinforcing means for the upper portion of said top wall, a connection between said reinforcing means and said cover wall, jointure strips for said top and side walls, and detachable fas-

tening means for connecting said cover wall to said jointure strips.

7. A wall tent having top and side walls, said top wall being of foraminous material, a cover wall for said top wall, means connecting portions of said cover wall to said top wall adjacent the ridge of the tent, the remaining sides thereof being normally free thereby to enable said cover wall to be thrown back and reveal the foraminous top wall for affording light and air to the interior of the tent, and detachable means for securing the end edge of said cover wall upon said top wall.

8. A wall tent having top and side walls, said top wall being of foraminous material, a cover wall for said top wall, means connecting an intermediate portion of said cover wall to said top wall adjacent the ridge of the tent, the remaining sides thereof being normally free thereby to enable said cover wall to be thrown back and reveal the foraminous top wall for affording light and air to the interior of the tent, and detachable means for securing the free sides and end edge of said cover wall upon said top wall, said detachable means including fasteners for the end edge of said cover wall adapted to relieve said top wall of a portion of the strain and transfer same to said cover wall.

9. A wall tent having top and side walls, at least a portion of said top wall being of foraminous material, a cover wall for said top wall and adapted to cover said foraminous material, means connecting the upper end portion of said cover wall to said top wall, the remaining sides being normally free, thereby to enable said cover wall to be thrown back and reveal the foraminous top wall for affording light and air to the interior of the tent, and detachable means for securing the end edge of said cover wall upon said top wall.

In testimony whereof I have hereunto signed my name to this specification.

ISIDORE PETER SMITH.
